UNITED STATES PATENT OFFICE.

WARREN C. SCHERER AND EVELYN D. SCHERER, OF CHICAGO, ILLINOIS.

HAIR WAVER.

Application filed August 16, 1924. Serial No. 732,353.

Our invention relates to improvements in hair wavers, and more particularly to that type of waver around which hair is to be curled and retained on the head for a period 5 of time.

The primary object of our invention is the production of a hair waver particularly desirable for waving short or bobbed hair, and owing to its construction, for permitting 10 the extreme ends of the hair to be waved.

Another object of our invention is the provision of a hair waver of the type mentioned, which has a flexible body portion and a clasp applied to said body portion 15 and so arranged that it will clasp the extreme ends of hair, and wave or crimp said ends as well as other portions of the hair curled around the device.

A still further object of our invention is 20 the provision of a device of this kind, which is cheap, easily applied to the hair and conveniently manipulated for curling the same.

The invention consists in the novel features of construction and in the arrangement 25 and combination of parts to be hereinafter described and more particularly pointed out in the subjoined claims.

In the drawings:—

30 Fig. 1 is a perspective view illustrating the application and use of the invention.

Fig. 2 is a detached perspective view of the device, showing the major part of the 35 flexible body portion positioned at an angle to the clasp to permit the insertion of hair therebetween.

Fig. 3 is a perspective view of the device showing the position of parts thereof when crimping or curling hair.

40 Fig. 4 is a detached perspective view of the clasp.

Figs. 5, 6 and 7 are enlarged transverse sections through the device, showing three 45 steps in the operation of crimping hair by means of the same; first, the manner of placing the hair between the body portion and the clasp; second, the manner in which the extreme ends of the hair are clasped between the body portion and the clasp, and 50 third, the manner of curling the hair around the body portion and clasping and retaining the same in curled or waved condition by the ends of said body portion.

Referring to the drawings in detail, the 55 reference numeral 10 designates a flexible

member or body portion, which may be of any suitable material, but is preferably constructed of an insulated copper wire covered with heavy silk and forming a single strand, the ends thereof being finished by applying 60 a coat of glue thereto, as at 11, to prevent fraying of the silk covering. If desired, the glue may be further covered with a coat of black shellac, thus imparting to the device 65 a distinctive appearance. This flexible member or body portion is preferably of cylindrical formation in cross section.

12 designates the clasp, which is formed of a length of wire bent upon itself to form an elongated loop having parallel side bars or 70 members 13 and rounded ends 14, the ends of the wire forming said loop being connected together midway between the ends of one side bar or member by applying to said ends a sleeve 15 soldered to said side bar; 75 but, if desired, the ends may be brought together in abutting relation and welded, soldered, or otherwise connected together. The rounded end portions of the elongated loop are recurved or rebent upon themselves, 80 as at 16, to form hook-shaped stops or retainers 17. The distance between the parallel side bars or members 13 is slightly less than the diameter of the flexible member or 85 body portion 10, and said member or body portion is positioned within the clasp 12 by being forced inwardly between the said parallel side bars or members 13. The extreme rounded ends of the hook portions 17 prevent movement of the flexible member or 90 body portion 10 outwardly in one direction, while the recurved or rebent portions 16 prevent movement of said flexible member or body portion laterally in either direction. Said flexible member or body portion is 95 therefore retained within the clasp due to the fact that it is held against movement in three directions by the hook-shaped stops or retainers 17, and in the fourth direction due to the fact that the diameter of said 100 member or body portion is slightly greater than the space between the flexible side bars or members 13 of the clasp. However, by grasping either end of the flexible member or body portion and drawing the latter outwardly from between said side bars or members, said flexible body portion can be removed from the clasp.

When preparing to wave short or bobbed hair, one end of the flexible member or body 110

portion is taken hold of and drawn outwardly, while the other end is retained in the clasp, as shown in Fig. 2. This provides a space 18 between the flexible member or body portion and the clasp so that said clasp will lie underneath a portion of the hair to be waved in close proximity to the ends thereof and the flexible member or body portion will extend crosswise over the portion 10 of hair to be waved.

Opposite ends of the clasp are to be exposed from opposite sides of the portion of hair to be waved, and the flexible member or body portion is then to be forced inwardly with the hair between said flexible member or body portion and said clasp, as shown in Fig. 5. The flexible member or body portion is then forced into the clasp with the end portions of the hair surrounding it, and with the extreme ends between the body portion and one of the side bars or members of the clasp, as shown at 19, Fig. 6. When the flexible member or body portion is forced into the clasp, the end portions of the hair are curled around said member or body portion and forced firmly thereagainst and around the same by the side members or bars of the clasp, as clearly shown in Fig. 6. After this step in the operation, the device is firmly clasped onto the ends of that portion of hair to be waved, and it is simply necessary to grasp opposite ends of the flexible member or body portion and rotate the device upwardly toward the scalp so as to curl the hair around the device, as shown in Fig. 7. When the hair is thus curled, the ends of the flexible member or body portion are bent over the curled hair, as shown in Figs. 3 and 7; thus retaining the device on the head, with a portion of the hair curled or crimped around the device.

The device, with the hair curled around the same, is left upon the head for a period of time so that the hair will assume a wavy condition. The device is easily removed from the hair as it is simply necessary to unbend the ends of the flexible member or body portion, grasp said ends and rotate the device in a direction opposite to that in which it was rotated for curling or crimping the hair, until it leaves the hair. The hair will be found hanging from the head in a wavy condition, the most pronounced portion thereof being at the extreme ends of the hair, due to the fact that these ends are closely rolled and clasped against the body portion of the device, as clearly shown in Fig. 6.

In Fig. 3 I have shown the ends of the flexible body portion bent to that side of the clasp having the elongated space between the side bars or members of the clasp, but it will be clear that these ends may be bent 60 at either of the three remaining sides. The

direction in which the ends of the flexible body portion are bent will naturally depend upon the position of the device when it reaches the scalp after the hair is curled around the same. 70

While our device is particularly adapted for use in waving short or bobbed hair, due to its construction permitting the extreme ends of the hair to be waved or crimped, it is to be understood that the flexible member 75 or body portion may be removed from the clasp and used separately for curling long hair. The device is therefore what may be considered a universal hair waver, but when using the clasp in connection with the flexible member or body portion, the extreme ends of bobbed hair are waved or crimped as effectively as the remaining portions of the hair. 80

Having thus described our invention, what we claim is:— 85

1. A hair waver comprising only two members, one a flexible member of cylindrical formation and the other a clasp removably applied to said flexible member and of less length than the same, said clasp being formed of wire and having parallel side members between which said flexible member is retained and between which parallel side members and said flexible member hair 95 in physical contact with both is adapted to be clasped and around all of which the hair is to be curled, the ends of said flexible member being adapted to be bent backwardly upon the hair curled around said flexible member and the side members of said clasp. 100

2. A hair waver comprising a flexible member of cylindrical formation and a clasp removably applied to said flexible member along the intermediate portion thereof, said clasp being formed of wire bent into an elongated loop to provide two parallel side members and having the ends of said loop rebent to form hooks at the ends of said clasp, said flexible member being positioned 110 within said clasp and bearing against the ends of said hooks and between the rebent portions of said hooks. 105

3. A hair waver comprising a flexible member of cylindrical formation and a clasp applied to the intermediate portion of said flexible member, said clasp being formed of wire and comprising two spaced parallel side members and hooks at opposite ends of said side members, said flexible member being forced into said clasp against the hooks thereof and being retained against movement in three directions by said hooks and against movement in the fourth direction by said side members. 115 120 125

4. A hair waver comprising a flexible member of cylindrical formation and a clasp removably applied to the intermediate portion of said flexible member, said clasp being formed of a piece of wire bent into an elong- 130

gated loop to provide two parallel side members, the ends of said wire being connected together at one of said side members and the elongated loop having its ends bent upon 5 itself to form hooks at one side of said side members, said flexible member being of slightly greater diameter than the space be-

tween said side members and being forced into the clasp against said hooks through the space between said side members. 10

In testimony whereof we affix our signatures.
